UNITED STATES PATENT OFFICE.

ANDREW CRANE, OF PRICHARD, IDAHO.

HAMMER SAW SET AND STRAIGHTENING DEVICE.

Application filed September 2, 1927. Serial No. 217,125.

The object of this invention is to provide a device adapted to be used with a hammer, for setting and correcting certain defects in the teeth of a cross cut saw, the device having 5 portions for correcting certain other defects without the aid of a hammer.

It is a feature of my invention to provide such a device in the form of an integral tool body in which all the integers of my invention 10 are embodied.

The improved device is equipped with an anvil-like abutment against which a tooth to be set may abut, one portion of the abutment receding or being so inclined from the 15 major portion as to form clearance to permit the pointed end of the tooth to be "set".

A further feature consists in means for enclosing a bent tooth to straighten the same, said means providing clearance at different 20 depths whereby any extent of length of the tooth may be corrected without injury to the point thereof.

A further feature consists in means for correcting the alinement of the raker teeth 25 should the latter become bent out of line, and for also correcting the edge portions of said teeth.

The invention has many other objects and 30 features which will be more fully described in connection with the accompanying drawing and which will be more particularly pointed out in and by the appended claim.

In the drawing:

Fig. 1, is a view in side elevation of one 35 form of my improved tool body.

Fig. 2, is an edge view thereof looking from the left of Fig. 1.

Fig. 3, is an edge view looking from the right of Fig. 1.

Fig. 4, is a fragmentary side view showing 40 how the device is used to "set" a tooth.

Fig. 5, is a fragmentary side view showing how the device is used to straighten a tooth.

Fig. 6, is a view of a portion of a cross 45 cut saw showing a raker tooth and the manner in which the device is used to correct a deformation thereof.

Fig. 7, is a view showing how the device is used to aline the raker teeth.

50 Like characters of reference designate similar parts throughout the different figures of the drawing.

My improved tool body consists of a head which is generally designated at 1, and a 55 shank or handle which is generally designated at 2. The handle 2, extends down-

wardly from the head 1, at a convenient angle so that when the user grips the handle he can not only support the head in proper relation to the saw but he can exert stress 60 to keep the head in position thereagainst.

First describing the head 1, the same is provided with what I will term a top face or edge 3 which junctures at 4, with the outer face 5, of the handle 2. The head 1, 65 has an extension 6, which projects below the juncture 7, of the handle with said head and the outer or front face 8, of said head constitutes a flat abutment section adapted to be located against the flat side of a saw 70 tooth, or rather against the shank 9, of the tooth. Said section has a receding portion 10, which is abreast of the tapered point 11, of the tooth of the saw and which permits of the saw tooth point being hammered and 75 bent to form the "set" of the tooth, as clearly shown in Fig. 4.

Assuming that a saw tooth has become accidentally bent as regards its shank 9, between its point and base, then, such tooth 80 must be hammered into a straightened position, for which special means is provided, as will now be explained.

Said head 1, has an angularly disposed tooth straightening section 12, of concave 85 form, which junctures at 13, with section 10, and at 14, with top face 3, and hence said section 12 may be said to be contiguous therewith.

Thus it will be seen that section 12 is angularly disposed with respect to section 10 and face 3 so that by gripping the handle 2, the user can conveniently employ either section 8 or 12, in performing the function of the tool. In Fig. 5, I have shown a bent tooth with the section 12 disposed in a manner against said tooth so that 90 said tooth may be hammered into a straightened position.

The concave form of section 12 affords the requisite clearance so that the tooth can be straightened without flexing 95 the tooth in a manner reverse to that shown in Fig. 5. If section 12, were flat, its performance would be less satisfactory.

Suppose a tooth of the saw became bent out of the plane of the saw, at the base of the tooth, or at a point above the base, and the bend was a relatively sharp bend, then, a means with which my tool body is provided would then be employed, as I will next describe.

105 The head 1, and extension 6, is provided with a slot 15 extending upwardly from

the lower edge 16. Said slot is proportioned to snugly "take" a tooth for the full height thereof and extends laterally clear through the head 1 from side to side thereof.

5 In order to protect the points of the teeth, the slot 15, is provided with enlargements 17 and 18, at different depths thereof. Thus, where a tooth was sharply bent out of the saw plane fairly near the point, the

10 latter would be protected by the enlargement 17 by reason of the fact that said enlargement would afford such clearance that the point of the tooth would not come into engagement with any portion of the tool

15 while the tooth was being bent into the saw plane. If the bend were near the base of the tooth, then, the tool body would be positioned as shown in Fig. 1, so that the top enlargement 18, would come into play.

20 I do not wish to be limited to two enlargements as any number may be employed within the purview of the claim.

As is well known, the cutting teeth of a cross cut saw are interrupted by what is 25 called a "raker" tooth, which I have shown at 19, in Fig. 6. This tooth 19, is not a "set" tooth but always remains in the plane of the saw and it is provided with oppositely extending teeth portions 20. Sometimes these tooth portions 20, get out of alignment with each other and out of plane with the saw.

The device of my invention is provided with means for correcting this defect which 30 I will next describe in detail.

In the handle 2, I have provided a slot 21, which is adapted to be fitted over the raker tooth 19, as shown in Fig. 7. By

shifting the tool in either direction indicated by the arrows in Fig. 7, the teeth 40 portions 20 can be bent back into alinement.

Sometimes, the overhanging ends 22, of the raker teeth become deformed, and in that case, I shape the edges 23, of the handle 2, in a manner so that by disposing the 45 handle in the position shown in Fig. 6, I can reshape and correct such deformation.

It will now be seen that in one integral tool body, I have provided means for the performance of various functions in conditioning a cross cut saw, and I will next refer to the feature of the handle 2, which forms a straight edge 24, so that when this edge is adjusted against the face of the teeth, it can be determined if they are in alinement. 55

It is believed that the device of my invention will be fully and clearly understood from the foregoing description and while I have herein shown and described one specific form of my invention, I do not wish to 60 be limited thereto except for such limitations as the claim may import.

I claim:

In a hammer saw set device of the class 65 described, a tool body adapted to be gripped by the hand of the user and provided with a head, said head having a tooth bending or straightening slot provided with tooth end protecting enlargements at different depths thereof, whereby teeth of different length 70 may be straightened or whereby bent portions at different heights of a tooth may be straightened.

In witness whereof, I hereby affix my signature.

ANDREW CRANE.
